[57] CLAIM

The ornamental design for a tethered action toy, as shown and described.

DESCRIPTION

FIG. 1 is a perspective view of a tethered action toy showing my new design;

FIG. 2 is a side elevational view thereof shown on a slightly enlarged scale, the side opposite being substantially a mirror image;

FIG. 3 is a bottom plan view thereof.

The tether member has been omitted from FIGS. 2 and 3 for ease of illustration.
